CLAIM

We claim the ornamental design for a lower rear suspension link for a model vehicle, as shown and described.

DESCRIPTION

FIG. 1 is a top, left, rear perspective view of a lower rear suspension link for a model vehicle;

FIG. 2 is front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a top, left, front perspective view; and,

FIG. 9 is a lower, left, front perspective view thereof showing the lower rear suspension link for a model vehicle within a broken line environment of use.

In the drawings, the broken line showing of features of the lower rear suspension link for a model vehicle illustrate portions of the lower rear suspension link for a model vehicle that form no part of the claimed design; whereas, the broken lines showing a model vehicle in FIG. 9 are included to illustrate environmental structure and also form no part of the claimed design.
